UNITED STATES PATENT OFFICE.

MEYER S. ROSEN, OF NEW YORK, N. Y., ASSIGNOR TO EMIL GROSSMAN M'F'G CO. INC.,
OF BROOKLYN, NEW YORK, A CORPORATION OF NEW YORK.

DESIGN FOR A MIRROR-BRACKET ARM.

50,250.

Specification for Design.

Patented Jan. 30, 1917.

Application filed October 21, 1916. Serial No. 127,027. Term of patent 14 years.

To all whom it may concern:

Be it known that I, MEYER S. ROSEN, a citizen of the United States, residing at Bronx borough, in the city and State of New York, have invented a new, original, and ornamental Design for a Mirror-Bracket Arm, of which the following is a specification, reference being had to the accompanying drawing, forming a part thereof, and in which—

Figure 1 is a top view, and Fig. 2 is a front elevation of a mirror bracket arm embodying my design.

I claim:

The ornamental design for a mirror bracket arm, as shown.

MEYER S. ROSEN.

Witnesses:

ALPHAEUS W. CLARK,
PAUL PELLERITO.
